APPARATUS FOR PROCESSING OILS

Russell P. Dunmire, Alliance, Ohio, assignor, by direct and mesne assignments, to The Buckeye Laboratories, Inc., a corporation of Ohio

Application August 15, 1940, Serial No. 352,823

5 Claims. (Cl. 196—16)

My invention relates generally to an improved apparatus for the treatment of hydrocarbons, and has for one of its objects the refining or re-refining of such materials.

More specifically this invention relates to the treatment of mineral hydrocarbons of a lubricating nature or of an insulating nature, vegetable oils and fats, waxes, etc., all of which are subject to more or less deterioration when exposed to air, moisture, metals or other agents which cause contamination such as oxidation, polymerization, etc., or contamination by solid materials in suspension.

Take, for example, lubricating oils, it has been found that although the most modern methods may be used in the treatment of these oils, yet certain undesirable properties remain in such lubricants which should be removed. It is appreciated by those skilled in the art that, in use, lubricating oils are subject to contamination by water, both free and in solution, metal particles, dust and other impurities such as air both free and dissolved. I have found also that varying shock loads detrimentally affect such oils. Under such trying conditions many contaminants appear in the oil which deleteriously affect the same so far as its use as a lubricant is concerned. I shall make no attempt to exhaust the subject but I might say that some of these contaminants are sludges caused by excessive heating, free and amorphous carbon, stable and unstable emulsions, polymerization products, soluble and insoluble resins and gums, acids, soaps, asphaltic sludges, etc. Free acids, dissolved gases and free water as well as other contaminants also are present in the oil. Lubricating oils also become discolored with use. So far as lubricating oils are concerned, the presence of these various materials causes excessive bearing wear, overheated bearings, increases internal oil friction and reduces the film strength.

Respecting insulating oils: Such oils are subjected to contamination and deterioration as the result of contact of the heated oil with air or certain other gases, both free and in solution, and by reason of its contact with metal surfaces. For example, in the case of circuit breakers, I have found that the presence of air which contains water vapor, oxygen, nitrogen, dust, etc., causes slow sludging and water condensation. The arc action of the circuit breaker produces carbon in suspension and precipitated; the carbon is also precipitated on the terminals and oil gas and hydrogen are produced as well as some unsaturates. The effect of all of this is rapid

oil deterioration from the arc, carbonization of the oil, decreased rupture capacity, explosion hazard and possible failure of the breaker. Again in the case of electric transformers, water, gas in solution, organic fluids and volatiles, organic acids, sludges, resinous bodies, compounds, tars, pitches and oxyasphaltic compounds are produced due to the heat from operation of the transformer. This, of course, lowers the insulation value of the oils, increases the power factor or dissipation factor, prevents proper heat dissipation and induces gas pocket formation, creates explosion hazards and volatile corrosion, promotes power factor losses and possible failure of the equipment. I might mention also that in the case of oils insulated electric cables the high electric stresses due to operation of the cable cause deterioration of the insulating oils in much the same fashion as in the case of transformers, the effect of which may be failure of the cable due to ionization, wax formation, a decrease in resistivity and an increase in power factor.

I have discovered in connection with fats and waxes that the products of oxidation together with free water and dissolved gases cause discoloration of the fats and waxes and in many cases liberate unsaturated compounds and form insoluble resins, gums, soaps and various types of sludge impurities.

30 The present invention provides an apparatus for the removal of the impurities or contaminants above referred to and is useful for the treatment or refining of new and unused oils as well as the rerefining of used oils.

35 Several embodiments of my invention have been shown in the accompanying drawings but in all forms my invention comprehends the treatment of oils by adsorption treatment with the utmost efficiency. It might be mentioned that 40 treatment of oils by adsorption is more easily handled than by treatment by other methods and is of decided advantage over other methods in that it does not involve the hazards encountered in the rerefining of oils wherein, for example, alkalies and acids are employed. The adsorptive treatment has this further advantage that it removes many undesirable constituents instead of merely changing them to temporarily inactive forms.

50 My apparatus involves the removal of water, light volatile unsaturates, kerosene and products of a like nature by low temperature vacuum distillation. Higher boiling, high molecular weight compounds such as sludges, acids, waxes, soaps, varnish, gums, resins and polymerized

compounds built up during service or use and excessive oxidation are removed by adsorption.

The removal of solid substances such as dust, grit, metallic particles and most colloidal size substances by the use of my apparatus produces, when treating unused oil, a better product than produced by equipment now in use, and when I employ my apparatus for the rerefining of used oils I find that I am able to produce a product which is better than the original.

As above mentioned, several embodiments of my invention have been illustrated in the accompanying drawings.

Fig. 1 is one embodiment of my invention in part sectional elevation;

Fig. 2 is a similar view of another embodiment of the invention;

Fig. 3 is a part sectional elevational view of still another embodiment of my invention; and

Fig. 4 shows in part sectional elevation a further embodiment of the invention.

Referring to the drawings in detail and first of all to the embodiment of my invention illustrated in Fig. 1: 2 designates a storage tank for the oils to be treated. This tank carries a hand or power operated pump 4, the discharge side of which is connected through the line 6 to a slurry mixer 8, whereby the oils may be transferred or conducted to the mixer. The tank 2 is preferably of sufficient capacity to permit precipitation of solid materials and sludges and is preferably heated as by steam, for example, to reduce operating costs.

The slurry mixer 8 is in the form of a closed container equipped with paddles 10 adapted to be rotated, for example, through the medium of hand crank 12. The slurry mixer 8 is of sufficient capacity to accommodate a batch of the oils to be treated plus the maximum amount of adsorbent material required.

The adsorbent material from any suitable supply source is introduced into the slurry mixer through a suitable opening 9 in the top of the mixer. After the slurry mixer has been charged the paddles 10 are actuated by the crank 12 until the oil and adsorbent material are thoroughly mixed.

Various materials may be employed as the adsorbent medium such, for example, as bone char, carbon black, fuller's earth or such materials known commercially as "Filtrol."

14 designates a closed retort connected to the bottom of the mixer 8 by pipe line 11 for the transfer of the slurry from the slurry mixer to the retort.

The retort 14 is electrically heated by electric heaters 15 thermostatically controlled by thermostat 16 so as to prevent overheating of the retort and injury to the material being treated therein. The retort, it will be understood, in practice is heat insulated so as to decrease heat radiation losses.

Mounted on the top of the retort is an electric motor 18 of the explosion-proof fan-cooled type.

This motor is mounted vertically and connected to its armature shaft and extending vertically downwardly into the retort is a shaft 20 carrying a foam breaker 22 near the upper end of the retort, a propeller 28 at its lower end adjacent the retort outlet 26 and an intermediate impeller 24. The retort is further equipped with a steam generator 30 to which water is supplied by water measuring device 31. This device is a forced feed type measuring chamber equipped

with a proper size orifice for controlling the rate of flow of water to the steam generator.

The agitator or impeller 24 is designed to agitate the oil at the proper velocity to secure the most efficient rate of heat transfer and also to obtain maximum contact of the oil with the adsorbent material with the minimum amount of adsorbent material. The adsorbent material may or may not be activated.

10 Transfer of the slurry from the slurry mixer 8 to the retort 14 is conveniently effected by air pressure, an air compressor (not shown) being employed in the line 32 communicating with the top of the slurry mixer.

15 After a batch of slurry has been made up in the mixer 8, air pressure is applied thereto through the line 32 to effect transfer of the slurry to the retort through the line 11. The motor 18 and electrical heaters 15 are then energized.

At one side of the retort 14 and mounted upon the housing 94 I provide a condensate tank 34 equipped in its upper part with condenser coils 36. Mounted on the top of this condensate tank is a vacuum pump 38 driven by electric motor 40.

20 The condensate tank 34 is supplied with water from a suitable source of supply by way of pipe line 42, this water flowing through an oil cooler 44 which is mounted adjacent the slurry mixer 8, the water passing from the oil cooler by way of line 46 to the condensate tank.

25 After the agitator motor 18 is started and the electric heaters 15 have been energized, the motor 40 driving the vacuum pump 38 is started and the valve 43 in the water line 42 is opened to admit cooling water to the condensate tank 34. It is to be noted that during heating and contacting the oil in the retort 14 the discharge valve 48 for the retort 14 remains closed. As the oil and adsorbent material in the retort 14 are being

30 heated and agitated certain gases or light volatile constituents are driven off or removed by means of the vacuum pump 38 which is connected to the retort through a tracefier or series of baffles 50 which is a device for separating globules of liquid from gases. The bottom of this tracefier is connected through a valve 52 with the retort so that the collected liquids in the tracefier will drain back to the retort for re-treatment.

35 The gases drawn off by the vacuum pump pass through the pump to the condenser 36 where the condensable constituents change from vapor to a liquid and collect in the condensate tank 34 from the bottom of which they may be drained periodically through drain 35.

40 Sight glass 54 is provided on the side of the condensate tank for observing the rate at which the distillate is drained from the condenser to the condensate tank 34. Provision is made to vent the distillate to atmosphere through pipe 56 which communicates with the interior of the tank.

45 The development of excessive pressure in the retort 14 is prevented by relief valve 58.

After the material in the retort 14 reaches the proper temperature, water from source 42 is introduced into the steam generator 30 to be released therefrom in the form of superheated steam which thoroughly strips the gases from the oil and aids in the deodorization of the oil.

50 The material in the retort 14 is now ready to be separated from the adsorbent material.

Carried by the housing 94 just below the outlet valve 48 of the retort 14 is a primary filter 60.

This filter is in the nature of a dome-like structure having a bottom 62 which is adapted to be raised and lowered through toggle mechanism 64 conveniently actuated by a hand wheel 66 which is at the exterior of the housing 94.

The filter medium is designated 68 and takes the form of a web of paper, cloth or very fine mesh screen extending from supply reel 70 across the upper face of the bottom 62 of the filter to take-up reel 72. When the filter 60 is to be operated, toggle mechanism 64 is operated to close the bottom 62, the filter medium 68 functioning not only as a filter but as a sealing gasket. One form of filter medium 68 which I have employed very successfully is kraft filter paper. This contains no coloring matter or chemicals that will injure the oil. With the bottom 62 in closed position the discharge valve 48 for the retort 14 is opened to admit of the discharge of the oil and the adsorbent material from the retort 14 into the filter 60. It will be understood that the filter 60 is of the proper capacity to accommodate the batch of material discharging from the retort 14. The oil passing through the filter medium 68 flows to the oil cooler 44 already referred to by way of the line 74. In this connection I might add that I find the paper 68 successfully prevents the discharge of solid materials while the filter cake is being formed on the paper.

The purpose of providing the oil cooler 44 is to cool the oil so as to reduce oxidation resulting from exposure to the air while the oil is in a highly heated condition. This oil cooler 44 consists of steel coils within a steel chamber. The cooling surface has sufficient area to cool the oil to a temperature below which it will not be readily oxidized by contact with air. As above mentioned, water from a suitable source of supply is used as the cooling medium.

Connected to the bottom of the oil cooler 44 is a secondary filter 76. This filter is of the glass cloth type and is employed as a precautionary measure absolutely to prevent likelihood of any solid materials from being discharged with the oil leaving the equipment. Such particles of materials would, of course, cause serious damage to expensive machinery in which the oil may be used. This filter is installed in a fabricated steel case and is readily removable for washing and cleaning. This glass cloth is not affected by oil, alkali, acids or solvents and may be readily cleaned therefore by washing in gasoline or kerosene, or, if desired, by back-blowing with steam or with air from the air line 32.

After leaving the filter 76 the liquid passes by way of pipe 78 through a look box or sight glass 80 to an additive gauge or proportioning device 82 and from thence to the clean liquid storage tank 84. The additive device 82 contains oxidation material such as hydroquinone, for example, and materials capable of restoring the oiliness of the oils being treated or to add to or increase the oiliness of the oils such as alcohols, esters and ketones. The additive may be introduced into the oils by opening the valve 86 which is in the line connected to the air line 32.

Referring again to the primary filter 60, the bottom 62 is provided with a series of graduated metallic screens 88 which lie beneath and support the filter medium 68. These screens avoid danger of the medium 68 being punctured when paper is used even when the apparatus is operating at high filtration pressures.

It is to be noted also that the filter medium 68 passes over guide rollers 90 so as properly to

control the position of the filter medium 68 with respect to the bottom 62 of the primary filter.

In the treatment of the material in the retort 14 care is exercised that the temperature of the material be kept below the flash point of the oils being treated and as will be understood the thermostat 16 is properly set for this purpose. The temperature of the mixture in the retort 14 is approximately within 50° to 150° of the flash point of mineral oil.

After a batch of material has been treated and the clean material stored in the tank 84, the discharge valve 48 of the retort 14 is again closed and the bottom 62 of the filter is lowered. Take-up roller 72 may then be rotated so as to draw the dirty filter medium and filter cake away from the face of the bottom 62, replacing the same with clean filter medium, the dirty filter medium being wound up on the rewind roll 72 and the filter cake being discharged into refuse tank 92. The apparatus is then ready for another cycle of operation.

The slurry mixer 8, oil cooler 44, the secondary filter 76, refuse tank 92 and the bottom of the primary filter 60 are all enclosed in the casing 94, above referred to, and the top of which provides a support for the primary filter 60, the retort 14 as well as the condensate tank 34, condenser 36, vacuum pump 38 and driving motor 40 therefor. This casing or housing is provided with a vent pipe 96 for conducting any fumes from the housing to the atmosphere.

The apparatus of Fig. 2 is the same in all respects as that just described except for the fact that the vacuum pump 38 is mounted beneath the condensate tank 34 and is operable as a vacuum pump to maintain a reduced pressure in the retort 14 or as an air compressor to effect transfer of the slurry from the slurry mixer 8 to the retort and to force the material in the filter 60 through the filter medium by air pressure and to provide for back-blowing the secondary filter 76.

It will be seen from an inspection of Fig. 2 that the low pressure side of the pump 38 has a line 98 which is equipped with a valve 100 and is connected to the lower end of the condenser coil 36. The upper end of this coil is connected to tracerfier 50. Connected to the other side of the pump 38 is a line 102 equipped with valves 104 and 106 and in communication with the upper part of the slurry mixer 8. Branching from this line 102 is line 108 equipped with valve 110 and in communication with the upper part of the body of the filter 60. The line 102 also has a branch 112 equipped with valve 114, this branch 112 leading to the top of the secondary filter 76.

In the use of this apparatus when the slurry in the mixer 8 is to be transferred to the retort 14 the pump 38 is operated as a compressor at which time air inlet valve 118, valves 104 and 106 will be opened, while valves 100, 116, 110 and 114 will be closed, so that the slurry will be forced out of the mixer to the retort. When the material in the retort 14 is being processed the pump 38 is operated as a vacuum pump under which conditions the valve 100 is open, the valves 110, 104, 106 and 114 are closed and vent valve 116 is opened, the pump under these conditions operating to draw the gases and light volatile constituents from the retort into the condenser 36.

In the primary filtering operation, the pump 38 is operated as an air compressor under which conditions the valves 100, 116, 104, 106 and 114 are closed and the valve 110 and air inlet valve

118 opened. This operation, of course, will force the material from the filter 60 by air pressure through the filter medium 68, oil cooler 44 and secondary filter 76 to storage tank 84. When it is desired to back-blow the secondary filter 76, 5 the pump 38 will be operated as a compressor, valves 118, 104 and 164 will be opened and valves 190, 116, 110 and 106 will be closed.

It is to be noted also that the vent line 56 for the condensate tank 34 in this embodiment 10 of my invention extends to the vent pipe 96.

In the embodiment of my invention illustrated in Fig. 3 the adsorbent material is added to the oil or other material being treated in the retort 14 as distinguished from employing the slurry 15 mixer 8 of Figs. 1 and 2.

120 designates a hopper for adsorbent material connected by conduit 122 to the retort 14. The conduit 122 is provided with metering valves 124 operated by lever 126 whereby a measured quantity of adsorbent material is metered out of the hopper for delivery to the retort. Operation of the pump 38 as a vacuum pump will, of course, effect transfer of the metered adsorbent material to the retort.

In this embodiment of my invention the material which has passed through the filtering medium 68 is drawn by way of pipe line 128 through an air oil cooler 130 which is driven by the motor 40 which drives the vacuum pump 38, 30 the oil after passing through the air cooler being discharged to the secondary filter 76 by way of the pipe line or conducting means 132.

The water for the condenser 36 is supplied by line 37.

In this embodiment of my invention the material charged into the filter 60 is forced through the filter by operating the pump 38 as a compressor.

Practically the entire equipment of Fig. 3 is 40 enclosed in a housing 134.

The apparatus of Fig. 4 is in general similar to the apparatus described in connection with Fig. 3 in that the adsorbent material is charged directly to the retort 14 instead of being mixed with the oil in a slurry mixer.

The vacuum pump 38 and its driving motor 40 are mounted directly on the top of the retort instead of, as in Fig. 1, being mounted on the top of the condensate tank. In this embodiment of my invention also I have omitted the filter medium 68 of the other figures of the drawings and I employ instead a removable filter cake 136 which is carried by the bottom 62 of the primary filter 60.

In this embodiment of my invention also the motor 18 drives the impellers, etc., in the retort 14 as well as the vacuum pump 38 instead of employing two motors as in the other embodiments of my invention.

It is to be understood that in the several embodiments of my invention above described changes may be made in the details of construction and arrangement of parts within the purview of my invention.

What I claim is:

1. In an apparatus for treating oils, the combination of a heated retort for the contacting of the oil and an adsorbent, a slurry mixer for slurring the oil and adsorbent material outside the retort, an air line for building up pressure in the slurry mixer to effect transfer of the slurry to the retort, a filter for filtering the material as the same is discharged from the retort, an oil cooler series connected to the filter, a second-

ary filter for filtering the cooled oil, a storage tank connected to the secondary filter, and a connection from said air line to the secondary filter for back-blowing the same.

2. In an apparatus for treating oil and removing impurities therefrom, the combination of a heated retort having an enclosed side wall, a top and a bottom for receiving an adsorbent material and the oil to be treated, said retort having an outlet opening located substantially in the bottom thereof, the side wall in the region of the lowermost part of the retort converging in a downward direction and meeting with the said bottom opening in the retort and forming a progressively constricted portion in advance of said outlet opening, a discharge valve having a movable member and a casing with a port extending therethrough connected in communication with the bottom opening in the retort, said casing of the valve being connected directly to the retort to minimize the space for the adsorbent material to clog the bottom opening in advance of the movable member of the valve, a motor mounted on the outside of the retort, a shaft driven by the motor and extending within the retort and terminating near the said bottom opening in the retort, an agitating device driven by the shaft well within the restricted portion of the retort to agitate the mixture of the oil and the adsorbent material during treatment and to substantially prevent clogging of the adsorbent material in advance of the valve, a vacuum pump connected to communicate with the retort to draw off the water and the low volatile impurities during treatment of the oil in the retort, and a filter connected to the valve below the retort to receive the mixture of the oil and the adsorbent material subsequent to treatment in the retort for separating the adsorbent material with its adsorbed impurities from the oil being treated to recover the latter.

3. In an apparatus for treating oil and removing impurities therefrom, the combination of a heated retort having an enclosed side wall, a top and a bottom for receiving an adsorbent material and the oil to be treated, said retort having an outlet opening located substantially in the bottom thereof, the side wall in the region of the lowermost part of the retort converging in a downward direction and meeting with the said bottom opening in the retort and forming a progressively constricted portion in advance of said outlet opening, a discharge valve having a movable member and a casing with a port extending therethrough connected in communication with the bottom opening in the retort, said casing of the valve being connected directly to the retort to minimize the space for the adsorbent material to clog the bottom opening in advance of the movable member of the valve, a motor mounted on the outside of the retort, a shaft driven by the motor and extending within the retort and terminating near the said bottom opening in the retort, an agitating device driven by the shaft well within the restricted portion of the retort to agitate the mixture of the oil and the adsorbent material during treatment and to substantially prevent clogging of the adsorbent material in advance of the valve, a steam generator, conduit means for introducing steam to the retort within the restricted portion thereof, a vacuum pump connected in communication with the retort to draw off the water and the low volatile impurities during treatment of the oil in the retort, and a filter connected to the valve below the retort to

receive the mixture of the oil and the adsorbent material subsequent to treatment in the retort for separating the adsorbent material with its adsorbent impurities from the oil being treated to recover the latter.

4. In an apparatus for treating oil and removing impurities therefrom, the combination of a heated retort having an enclosed side wall, a top, and a bottom for receiving an adsorbent material and the oil to be treated, said retort having an outlet opening located substantially in the bottom thereof, the side wall in the region of the lowermost part of the retort converging in a downward direction and meeting with the said bottom opening in the retort and forming a progressively constricted portion in advance of said outlet opening, a discharge valve having a movable member and a casing with a port extending therethrough connected in communication with the bottom opening in the retort, said casing of the valve being connected directly to the retort to minimize the space for the adsorbent material to clog the bottom opening in advance of the movable member of the valve, a motor mounted on the outside of and above the top of the retort, a shaft driven by the motor and extending downwardly through the top of the retort and terminating near the said bottom opening in the retort, an agitating device driven by the shaft well within the restricted portion of the retort to agitate the mixture of the oil and the adsorbent material during treatment and to substantially prevent clogging of the adsorbent material in advance of the valve, a vacuum pump connected in communication with the retort to draw off the water and the low volatile impurities during treatment of the oil in the retort, a filter positioned beneath the retort and the valve to receive the mixture of the oil and the adsorbent material subsequent to treatment in the retort for separating the adsorbent material with its adsorbed impurities from the oil being treated to recover the latter, an oil cooler connected to receive the filtered oil from the filter, and a secondary filter for filtering the cooled oil to render the finally treated oil in a clean state.

5. In an apparatus for treating oil and removing impurities therefrom, the combination of a heated retort having an enclosed side wall, a top and a bottom for receiving an adsorbent material and the oil to be treated, a slurry mixer for slurring the adsorbent material and the oil to be treated outside of the retort, a transfer conduit interconnecting the slurry mixer and the retort, means for establishing a differential pressure between the retort and the slurry mixer to transfer the slurry from the slurry mixer to the retort, said retort having an outlet opening located substantially in the bottom thereof, the side wall in the region of the lowermost part of the retort converging in a downward direction and meeting with the said bottom opening in the retort and forming a progressively constricted portion in advance of said outlet opening, a discharge valve having a movable member and a casing with a port extending therethrough connected in communication with the bottom opening in the retort, said casing of the valve being connected directly to the retort to minimize the space for the adsorbent material to clog the bottom opening in advance of the movable member of the valve, a motor mounted on the outside of the retort, a shaft driven by the motor and extending within the retort and terminating near the said bottom opening in the retort, an agitating device driven by the shaft well within the restricted portion of the retort to agitate the mixture of the oil and the adsorbent material during treatment and to substantially prevent clogging of the adsorbent material in advance of the valve, a vacuum pump connected in communication with the retort to draw off the water and the low volatile impurities during treatment of the oil in the retort, and a filter connected to the valve below the retort to receive the mixture of the oil and the adsorbent material subsequent to treatment in the retort for separating the adsorbent material with its adsorbent impurities from the oil being treated to recover the latter.

RUSSELL P. DUNMIRE.
